UNITED STATES PATENT OFFICE.

CONRAD DRESSLER, OF MARLOW, ENGLAND.

OVEN SUITABLE FOR USE IN THE MANUFACTURE OF TILES, POTTERY, AND ANALOGOUS WARE, AND FOR OTHER PURPOSES.

1,116,036.

Specification of Letters Patent.

Patented Nov. 3, 1914.

Application filed March 17, 1913. Serial No. 754,938.

To all whom it may concern:

Be it known that I, CONRAD DRESSLER, a subject of the King of Great Britain and Ireland, residing at Marlow, in the county 5 of Bucks, England, have invented Improvements in or Relating to Ovens Suitable for Use in the Manufacture of Tiles, Pottery, and Analogous Ware, and for other purposes, of which the following is a specification.

This invention has reference more particularly to ovens of the kind suitable for use in the manufacture of tiles, pottery and analogous ware but suitable also for other 15 purposes, for example enameling metal, annealing of glass and the like, in which combustion and heating chambers are arranged longitudinally within and structurally independent of the main chamber of the oven 20 so as to be free to expand and contract independently thereof and through which the products of combustion are drawn by exhausting means in one direction only, the chambers being arranged at opposite sides 25 of the passage-way through the main chamber in such manner that air will be heated and caused to ascend at the opposite outer sides of the chambers to the top of the oven, then descend among the goods on a vehicle 30 carrying the same and pass laterally from the vehicle beneath the said chambers to the outer sides thereof to be reheated and again circulated, as described in the specification of former Letters Patent No. 1,023, 35 628 of 1912 granted to me.

An object of the present invention is to facilitate uniform flow of heated air over and among the goods to be treated in order to effect a practical uniform heating there- 40 of and the production of goods of substantially uniformly good quality, in an easier and more reliable manner than heretofore.

Another object of the invention is to enable the combustion and heating chambers, 45 which are constructed of refractory material such as fireclay, porcelain, bauxite and the like, to be made thin yet strong, so as to facilitate the transmission of heat there- through, and also to allow for ready ex- 50 pansion and contraction thereof so as to avoid or minimize fracture of the chambers and consequent outlay in repairs and loss of time.

To enable the first mentioned object to be attained, the main chamber of the oven, 55 the combustion chambers therein and the vehicle or each vehicle used for carrying the goods to be heated, are so relatively constructed and arranged that the goods will be supported in the upper part of the oven 60 above or mainly above the level of the combustion chambers and the air heated between the outer sides of the combustion chambers and the oven wall will flow to the upper part of the oven and over and among the 65 goods therein and will thence descend through passages specially provided in the vehicle itself to horizontal outlets from which it will pass under the combustion chambers to the outer sides thereof to be 70 again heated and circulated, while heat radiated from the inner and upper sides of the chambers will be directed, to a large extent, against the underside of the platform or main platform on the vehicle carrying the goods and be thus utilized by con- 75 duction through the platform in heating the goods. Conveniently the combustion chambers may be curvilinear in transverse sec- 80

In the accompanying drawings, Figure 1 shows in cross section a tunnel oven with vehicle constructed according to the present invention. Figs. 2, 3, 4 and 5 are plan views taken on the lines A, A, B, B, C, C, and 85 D, D, respectively of Fig. 1 showing the construction of the upper portion of the vehicle for carrying the goods to be heated. Fig. 6 is a horizontal section, taken on the line E, E, of Fig. 1, of part of one of the 90 combustion chambers. Figs. 7 and 8 are cross sections showing modified constructions of combustion or heating chambers.

Referring to Figs. 1 to 6 inclusive, 1, 1 are the combustion and heating chambers 95 arranged longitudinally within and structurally independent of the main chamber 2 of the ovens and at opposite sides of the passageway 3 for the vehicles carrying the goods.

According to the constructional example shown in Figs. 1 to 5, the vehicle comprises a lower portion or truck adapted to travel on rails 4 and an upper portion. The lower portion may conveniently, and as shown, 100 comprise slabs 5 of refractory material car-

ried by a metal frame 5^a mounted on wheels arranged to run on the rails 4 and supporting transverse blocks 5^b of refractory material spaced apart to form a series of transverse horizontal passages 5^c. The upper portion of the vehicle may conveniently comprise a number of transverse walls spaced apart longitudinally and connected together at their central portions by vertical longitudinal walls forming between them a row of vertical passages communicating at their lower ends with the horizontal passages 5^c. The transverse walls may, as shown in Figs. 2 to 5 inclusive, conveniently be built up of blocks some of which, namely those marked 6, are made of rectangular or equivalent shape, as seen in plan, with vertical recesses 7 at opposite sides to receive the edge portions of vertical longitudinal plates 8 designed to form the sides of vertical passages 9, while other blocks, marked 6^a, may be of approximately I shape as seen in plan, and arranged in pairs, also to form vertical passages 9 between them, thus binding the whole structure together. The latter blocks have vertical recesses 7^a in their outer sides corresponding with the vertical recesses 7 in the blocks 6 to receive the edges of the adjacent plates 8. The blocks in one horizontal layer or course are arranged to break joint with those or some of those in the layer above or below. The lower end portions of the side walls 8 in the lowest set may be extended outwardly, as by longitudinal blocks 10, (Fig. 1) resting on the blocks 5^b, to better direct the hot air issuing from the passages 9 and 5^c to the passages 11 below the combustion chambers 1, whence it is drawn upward between these chambers and the side walls of the oven. The upper layer or course comprises transverse walls 6^b with interposed channel shaped blocks 6^c arranged in pairs to form continuations of the passages 9 formed by and between the blocks 6, 6^a and plates 8 below. Upon the transverse walls, which may, as shown, be of uniform width for part of their height and then gradually extend outward to follow more or less the shape of the adjacent side portions of the combustion chambers 1, are placed flat horizontal slabs 12 forming a platform, to carry the goods to be heated, above which may be supported additional horizontal slabs or platforms 13 to carry additional goods, the slabs having longitudinal openings 14 between them corresponding to and arranged above the vertical passages or flues 9.

The tunnel oven, as seen in cross section may, as shown in Fig. 1, have its side walls 14 for the greater portion of their height inclined inwardly and upwardly and carry an arch 15 of small curvature, the lower portions 14^a of the side walls bending more or less inward to the bottom of the oven, all with a view to facilitating circulation of hot

air around the combustion chambers 1, among the goods and through the passages or flues 9.

By the construction described, the air in the oven will be heated by heat conducted and radiated through the walls of the combustion chambers 1 and be thereby caused to rise between the said chambers and walls of the oven and then flow in a uniform manner over and among the goods and thence descend through the vertical passages 9 to the horizontal passages 5^c whence it will pass under the combustion chambers to again pass upward between the chambers and oven walls, as indicated by the arrows. At the same time, heat will be radiated from the inner and upper sides of the combustion chambers against the underside of the platform 12 for the purpose hereinbefore mentioned.

Each combustion chamber 1 may advantageously and as shown, be built up of curvilinear segments 16 fitted together at their edges and mounted upon suitable cradles or supports 17 spaced apart upon the ledge 18 at one side of the passageway 3 so as to form the air passages 11 beneath them. Conveniently, there may, as shown, be three segments of concavo-convex section, one segment being arranged to form the bottom and the other two to form the opposite sides of the chamber which, in cross section, is therefore of approximately triangular shape, but with outwardly convex surfaces. The adjacent edge portions of the lower and side segments may conveniently be arranged to interlock with each other so as to hold each other in place laterally, for which purpose the edge portions of the lower segment may be formed with right angled recesses 19 to receive correspondingly shaped projections or flanges 20 on the lower inner edge portions of the side segments. The upper edge portions of the side segments may simply abut against each other as shown at 21 and the joint be protected by a cover strip 22 which may be of crescent section and form a practically gas tight joint with the segments by sealing with sand. The segments 16 are or may advantageously be corrugated as shown, the corrugations extending transversely to the length of the combustion chambers, thereby providing large heat absorbing and radiating surfaces and enabling the segments to be made thin. The end portions 16^a of longitudinally adjacent sections are adapted to fit one into the other (see Fig. 6), as for example plug and socket fashion.

According to another construction, each combustion or heating chamber is made of a series of tubes of curvilinear or other suitable form in cross section with a thin slit extending longitudinally and partly through the wall thereof so as to form a longitudinal

line of weakness so that any fracture of the chamber that may take place through expansion or contraction under the action of heat shall take place along such line of 5 weakness, and in order to prevent the passage of air or hot gases through the fracture into the oven, the combustion chamber is provided externally with a longitudinal cover or closure arranged over the slit and 10 so as to form a gas tight joint with the chamber. Such a construction of combustion chamber is shown in Fig. 7 wherein 24 is the thin slit extending longitudinally and partly through the upper side of the chamber and 25 is the cover or closure for such slit. The longitudinal slit 24 may, as shown, extend partly through the wall of the chamber from the outer surface thereof and the cover or closure 25 be of concave channel 15 shape in cross section and have its longitudinal edges extending into a longitudinal groove 26. The groove may be formed in the chamber at the sides of the slit, but preferably, it may, as shown, be formed by 20 means of longitudinal ridges 26 on the chamber. The edges of the cover or closure are sealed by suitable material, for example sand or the like, contained in the groove. If desired, the longitudinal slit may extend 25 initially entirely through the wall of the chamber, as shown in Fig. 8.

A combustion or heating chamber such as just described can be made of any convenient length and of circular, oval, square, triangular or similar shape in cross section with the longitudinal slit, groove, ridges and cover at its upper side as shown. In the examples shown in Figs. 7 and 8, the chambers are of circular cross section. Chambers thus constructed may conveniently be used to form a longitudinal extension, or one of several longitudinal extensions, of a combustion chamber properly constructed as first herein described. Such chambers may however in 40 some cases be used for the combustion chambers proper as well as for the extensions thereof that serve as heating chambers.

By either of the constructions described, the wall of the combustion or heating chamber can be made comparatively thin to allow of efficient transmission of heat therethrough and yet afford considerable strength, while passage of air or other gases through the longitudinal slit in the chamber wall, 45 whether the chamber become fractured along the slit by expansion, or whether the slit be formed originally entirely through the wall, will be effectually prevented by the sealed cover or equivalent closing means 50 arranged over or opposite the slit.

The claims as hereunto appended, while referring only to combustion chambers are to be understood as covering heating radiating chambers generally, that is to say 55 whether combustion actually takes place

therein or whether highly heated gases only flow therethrough.

What I claim is:

1. A tunnel oven of the kind described, comprising a main chamber, combustion 70 chambers arranged longitudinally in spaced relationship therein and a goods-supporting platform partially overhanging the said combustion chambers whereby heated air ascending between the combustion chambers 75 and the adjacent side walls of the main chamber is diverted laterally over the platform.

2. A tunnel oven of the kind described, comprising a main chamber, combustion 80 chambers arranged longitudinally in spaced relationship therein, a goods-supporting platform partially overhanging the said combustion chambers and flues extending downwardly from said platform between the 85 combustion chambers, the platform and flues serving to cause heated air rising at the outer sides of the combustion chambers to enter the oven space above the platform and then to descend through the latter to the 90 oven region adjacent to the bottom of the combustion chambers.

3. A tunnel oven of the kind described, comprising a main chamber, combustion 95 chambers supported at a distance from the walls thereof and from each other, a goods-supporting platform partially overhanging the said combustion chambers and flues leading downward from the platform between the combustion chambers.

4. A tunnel oven of the kind described, comprising a main chamber, combustion 100 chambers arranged longitudinally in spaced relationship therein and having the sides thereof nearest to the center line of the oven of upwardly and outwardly convex shape and a goods-supporting structure having its opposite sides conforming in shape and closely adjacent to the said curved sides of the combustion chamber and its upper side or platform located at a height substantially level with the top of the combustion chambers.

5. A tunnel oven of the kind described, comprising a main chamber, combustion 115 chambers arranged longitudinally in spaced relationship therein and made of substantially triangular section with outwardly convex sides, a goods-supporting platform located at a height above and partially overlapping the combustion chambers and flues leading downwardly from the platform between the combustion chambers.

6. In a tunnel oven of the kind described, a goods-supporting platform comprising a 125 movable base, a cellular superstructure upon said base constituting vertical flues terminating at the bottom in lateral passages and horizontal slabs surmounting the cellular superstructure and having longitudinal 130

spaces between them corresponding to the said flues.

7. In a tunnel oven of the kind described, a goods-supporting platform comprising a movable base, a series of blocks supported by such base and forming transverse walls that are spaced apart longitudinally and increase in width with increase in distance from the base and horizontal slabs surmounting said transverse walls.

8. In a tunnel oven of the kind described, a goods-supporting platform comprising a movable base, a series of blocks supported by such base and forming transverse walls spaced apart by longitudinal walls, the said walls constituting vertical flues terminating at the bottom in lateral passages, and horizontal slabs surmounting the series of blocks and spaced apart to correspond to the said flues.

9. In a tunnel oven of the kind described, a goods-supporting platform comprising a movable base, a series of blocks supported by such base and forming transverse walls that increase in width with increase in distance from the base and spaced apart by longitudinal walls, the said walls constituting vertical flues terminating at the bottom in lateral passages and horizontal slabs surmounting the series of blocks.

10. In a tunnel oven of the kind described, a combustion chamber slit longitudinally for the purpose specified.

11. In a tunnel oven of the kind described, a combustion chamber slit longitudinally thereof, and a cover surmounting the slit.

12. In a tunnel oven of the kind described, a combustion chamber having a longitudinal slit at the upper part thereof and longitudinal ridges at opposite sides of said slit to

constitute a groove and a cover extending longitudinally over said slit and having its edges extending into said groove.

13. In a tunnel oven of the kind described, a combustion chamber having a three sided wall of curvilinear shape in cross section and of corrugated shape in longitudinal section, such wall comprising a bottom section the edge portions of which are formed with right angled recesses extending longitudinally thereof and two identical and interchangeable side segments also of corrugated shape in cross section and each formed at the lower edge with a longitudinal flange adapted to enter the corresponding recess in the bottom segment, the said side segments extending inwardly from the edges of the lower segment to an apex where they abut.

14. In a tunnel oven of the kind described, a combustion chamber comprising three curvilinear segments one having its longitudinal edges in a horizontal plane and the other pair extending inwardly from such edges to an apex where they abut, and a cover surmounting said apex.

15. In a tunnel oven of the kind described, a combustion chamber comprising three curvilinear segments, one disposed with its convex surface lowermost and having its longitudinal edges in a horizontal plane and the other pair extending inwardly from such edges with the convex surfaces outermost to an apex where they abut and a cover surmounting said apex.

Signed at London, England, this 6th day 75 of March 1913.

CONRAD DRESSLER.
